C. FLINT.
KINDLING BURNER.
APPLICATION FILED SEPT. 2, 1919.

1,389,427.

Patented Aug. 30, 1921.

UNITED STATES PATENT OFFICE.

CHARLES FLINT, OF MENOMINEE, MICHIGAN.

KINDLING-BURNER.

1,389,427.

Specification of Letters Patent. Patented Aug. 30, 1921.

Application filed September 2, 1919. Serial No. 321,152.

To all whom it may concern:

Be it known that I, CHARLES FLINT, a citizen of Sweden, and resident of Menominee, in the county of Menominee and State of Michigan, have invented certain new and useful Improvements in Kindling-Burners; and I do hereby declare that the following is a full, clear, and exact description thereof.

10 My invention relates to new and useful improvements in oil burners, more particularly of a simple and portable type.

It is in general the object of my invention to simplify and otherwise improve the structure and to increase the efficiency of devices of this character.

15 It is more particularly my object to provide a burner which may be inserted under the grate of a solid fuel stove for the purpose of kindling fuel therein, the burner being removable from the stove upon completion of the kindling operation.

It is further my object to provide an arrangement whereby a burner of this character may be detachably secured to any suitable support.

20 With the above and other objects and advantages in view, which will be apparent as the description proceeds, my invention resides in the novel features of construction, combination and arrangement of parts which will be hereinafter more particularly described and defined by the appended claims.

25 In the accompanying drawings:

Figure 1 is a view, partly in side elevation and partly in section of an oil burner embodying my invention.

30 Fig. 2 is a plan view of the burner head. Fig. 3 is a plan view of the modified form of the burner head.

35 Referring more particularly to the accompanying drawings, I provide a pipe casting 5 which forms the shank of the burner unit, and fitted in one end of this shank is a nipple 6 in which is screwed one end of an angle coupling 7, a valve plug 8 being secured in the other end of the coupling. This plug is provided with a flange

40 9 whereby the plug is secured in any suitable manner, as by welding or soldering, to the offset base portion 10 of a supply tank 11, this tank being provided with a filling opening 12 in one side which may be closed 45 in any suitable manner. The plug 8 is provided with a longitudinal bore 13 having

divergent branches in the upper portion of the plug, and a valve needle 14 is engaged in said bore to control the flow of oil therethrough, and consequently control the operation of the burner. This valve needle extends through the supply tank 11 and is threaded in a sleeve 15 secured on the tank, the upper end of the needle terminating in a finger-piece 16. A packing gland 17 is provided at the outer end of the sleeve 15.

The burner head of the device is formed by a flattened and upwardly directed terminal portion 18 of the shank casting 5, this terminal portion being cutaway at one side 50 to expose its interior, and a plate section 19 is secured by screws 20 to said cutaway side of the portion 18 whereby to afford exposure of the passageway thus provided, and this sectional structure of the burner head 55 is provided particularly for the purpose of permitting suitable asbestos or other wick material 21 to be packed therein and in the shank pipe section 5, it being noted that it would be extremely difficult otherwise to pack this material in the burner head in view of the oblong shape of its passageway as shown particularly in Fig. 2. For detachably securing the burner to the edge portion of the draft or door opening 60 of the stove or any other suitable support, an attaching bracket is provided comprising a single length of heavy strap metal 22 bent in U-shape and provided with apertures 23 in the intermediate portions of its 65 legs, snugly receiving the shank pipe section 5, it being particularly noted that this shank pipe section is oval in cross section whereby to prevent relative rotation of the shank pipe section and bracket, to thus hold 70 the tank 11 in raised position when the device is secured to a support member. A clamping screw 24 is threaded in the end portion of one of the bracket legs.

An exceedingly simple and efficient 75 burner device has thus been provided, which may be readily manipulated to kindle a solid fuel fire, or which may be readily secured to a convenient support to effect any emergency heating function.

80 While I have shown and described a preferred embodiment of my invention, it will be appreciated that various changes and modifications of structure may be employed within the scope of the appended claim, 85 without departing in any manner from the spirit of my invention, for instance, as

shown in Fig. 3, the burner head structure of the burner may be modified to provide a series of divergently elongated burner passageways 25, this modified structure being particularly adapted to be used as an oil stove for heating utensils or the like.

What is claimed is:

A burner of the class described comprising a tubular shank member, a laterally disposed burner head carried at one end of the shank member and having a long narrow slot for receiving a flat wick, wick packing disposed in said burner head and extending into the adjacent portion of the shank member, one side of the burner head being removable to permit the wick to be readily inserted, a supply tank carried by and upstanding from the other end of the

shank member, means for controlling flow of liquid from said supply tank, said shank 20 member being oval in cross section, a U-shaped bracket member provided with apertures in the intermediate portions of its legs which snugly receive the shank member, and a clamping screw threaded in the 25 end portion of one of the legs of the bracket member.

In testimony that I claim the foregoing I have hereunto set my hand at Menominee, in the county of Menominee and State of 30 Michigan.

CHARLES FLINT.
